UNITED STATES PATENT OFFICE.

GEORGE W. LEWIS, OF GRINNELL, IOWA.

GEARING FOR WASHING-MACHINES.

1,119,438.

Specification of Letters Patent.

Patented Dec. 1, 1914.

Application filed February 14, 1910. Serial No. 543,883.

To all whom it may concern:

Be it known that I, GEORGE W. LEWIS, a citizen of the United States, residing at Grinnell, in the county of Poweshiek and State of Iowa, have invented a certain new and useful Gearing for Washing-Machines, of which the following is a specification.

My invention relates to that class of gearing devices especially designed for use in connection with washing machines of the type having an agitator adapted to be given an alternating rotary movement and having an ordinary clothes wringer connected therewith.

My object is to provide a gearing device of this class of simple, durable and inexpensive construction that may be readily and easily applied to a washing machine and wringer of the class described.

More specifically it is my object to provide a gearing device of this class that may be applied to the stationary body portion of the washing machine and the hinged cover thereof in such a manner that the main power shaft may be easily placed in line with the pivotal center of the hinged cover.

A further object is to provide improved means for throwing the agitator shaft out of gear when the hinged cover is raised and placed in an open position.

My invention consists in certain details, in the construction, arrangement and combination of the various parts of the device whereby the objects contemplated are attained, as hereinafter more fully set forth, pointed out in my claims and illustrated in the accompanying drawings, in which:

Figure 1 shows a top or plan view of a part of the washing machine and the wringer to illustrate a modified form of my device. Fig. 2 shows an enlarged, detail, sectional view of the agitator shaft and connected parts illustrating the modified form. Fig. 3 shows a similar view, of smaller size, taken on a line at right angles to that on which Fig. 2 is taken, and showing the gear wheel on the agitator shaft in position to rotate in unison with the shaft. Fig. 4 shows a view similar to Fig. 3 of the agitator shaft in its inverted position as when the hinged cover is open and showing the agitator shaft moved downwardly to position where the gear wheel thereon may have an alternating rotary movement without moving the agitator shaft. Fig. 5 shows a sectional view on the line 13—13 of Fig. 2, and

Fig. 6 shows a sectional view on the line 14—14 of Fig. 2.

Mounted in the hinged cover of the washing machine is an agitator shaft 16. All of the parts just described are of the ordinary construction and of themselves form no part of my present invention.

My improved gearing device comprises a power shaft 17 provided with a crank arm 65 20 to which a pitman 21 is connected. This shaft 17 is continuously rotated by any suitable gearing devices within the casing 49. I support the power shaft by means of the brackets 22 and 31 fixed on the stationary 70 portion of the top of the machine body. The hinged members 37 may be fixed to the hinged cover and the cover will have its hinged center at the center of the power shaft 17 and may freely swing thereon. 75

The means for operating the agitator shaft and for throwing it into and out of gear comprises a segmental rack 39 fulcrumed to a lug 40 and arranged in upright position. This segmental rack is provided 80 near its central portion with a bolt 41 to which the pitman 21 is pivoted. The agitator shaft 16 is mounted in a stationary bearing 68 and is capable of a limited up and down movement therein and also of rotary movement. At the top of this bearing 68 is a gear case 69 open at one side as shown in Figs. 3 and 4. The upper end of the agitator shaft 16 is provided near its top with a longitudinal groove 70 and below this longitudinal groove is a recess 71 which, as shown in Fig. 6, extends around the agitator shaft about half its circumference. Mounted within the gear case 69 is a beveled pinion 72 having a key 73 therein 95 which key is designed to slidably enter the slot 70 when the shaft 16 is at its lower limit of movement and said key is also designed to enter the recess 71 when the shaft is moved upwardly relative to its bearing as shown in Fig. 4. The segmental rack 39 is normally in mesh with the pinion 72. In use and assuming that the cover is closed then the segmental rack 39 will engage the pinion 72 through the open side of the gear case and the shaft will be given an alternating rotary movement. Then when the cover is opened and thrown to an inverted position, as shown in Fig. 4, the weight of the agitator shaft will cause it to slide downwardly in its bearing, thus causing the key of the pinion 72 to enter the recess 71. The

segmental rack 39 will remain in mesh with the pinion and will impart an alternating rotary motion to it but the shaft 16 will not rotate because the key 73 may turn freely in 5 the recess 71 without moving the shaft. A pin 74 is placed in the top of the shaft 16 to limit the downward movement of the shaft.

I claim—

1. In a device of the class described, the 10 combination of a support, a hinged member for the support, capable of being swung to an inverted position, a pinion carried by said hinged member, an upright shaft capable of longitudinal movement through said 15 pinion, means for imparting an alternating rotary movement to said pinion, and means for causing said pinion and said shaft to rotate in unison when the hinged member is in its normal horizontal position, said means 20 being so located as to be inoperative when the hinged member is swung to inverted position and said shaft slides to one limit of its movement with relation to said pinion.

2. In a device of the class described, a 25 support, a hinged member for the support, an upright bearing on said hinged member having a casing at its upper end, a pinion within said casing, a shaft slidably mounted within said bearing and said pinion having a narrow groove and a wide groove in 30 communication therewith, a rack mounted on the hinged member and in mesh with said pinion, said parts being so arranged that an oscillation of the rack will impart 35 an alternating rotary movement to said pinion, a key in said pinion designed to enter the said narrow groove when the shaft is at one limit of its movement and to enter the wide groove when at the other limit of 40 its movement.

3. In a device of the class described, the 45 combination of a support, an upright shaft slidably mounted in the support, said shaft being provided with a narrow groove and with a wide groove communicating with it, a beveled pinion slidably mounted on the shaft, a key fixed to the beveled pinion and designed to enter the narrow groove when the beveled pinion is at the top of the shaft

and to enter the wide groove when the shaft 50 moves upwardly through the beveled pinion, a gear casing surrounding said beveled pinion and fixed to the support said casing being open at one side, a segmental rack in mesh with the beveled pinion, said parts being so arranged that when the support in 55 which the shaft is mounted is in normal position, the shaft will be at its lower limit of movement and the key will be in the narrow portion of the slot to thereby operate the 60 shaft when the beveled pinion is turned and when the said support is in an inverted position the shaft will move downwardly through the casing by gravity so that the key will be in the wide slot and so that the 65 beveled pinion may be rotatably reciprocated by the segmental rack without operating the shaft.

4. In a device of the class described, the 70 combination of a support, a continuously driven crank shaft thereon, a hinged member designed to swing from a horizontal position about said crank shaft as a center to an inverted position, an upright bearing on 75 said hinged member having a casing at its upper end, a pinion within said casing, a shaft slidably mounted within said bearing and said pinion, said shaft being provided with a narrow groove and a wide groove in 80 communication with it, a rack mounted on the hinged member in mesh with said pinion, a pitman for operating said rack from the crank to produce an alternating rotary movement of said pinion as the crank is rotated, a key fixed to the pinion designed to 85 enter the narrow groove in said shaft when the hinged member is in its horizontal position and to cause said shaft and pinion to operate in unison, said key being also designed to enter the wide groove when the 90 cover is in its inverted position to permit the pinion to rotate without rotating the said shaft.

GEORGE W. LEWIS.
